5 Claims. (Cl. 91—12)

1

This invention relates to paper bag making machinery.

Difficulties are experienced in paper bag making in keeping the paper web running in correct relationship to the former plate and to the line of paste applied from the seam adhesive device, which may be a paste box. These difficulties are due to inequalities in the paper and to indifferent winding. Their effect is to cause the paper to wander laterally on the former plate from time to time, sometimes causing the paste line to leave the web altogether or to appear too far inside the paper tube, depositing paste on the former plate and/or on the inside of the bag. In order to minimise this trouble it has hitherto been the practice to allow a liberal amount of paper for an overlap and to depend on the vigilance of the operator. Attempts have been made to control the position of the web of paper in its relationship to the former plate and the seam adhesive device, but owing to the reel being too remote from the tubing point they have failed to reduce the difficulties substantially.

The object of the present invention is to provide means for overcoming the difficulties mentioned.

Paper bag making machinery according to the present invention is characterised in that the seam adhesive device is movable laterally of the direction of travel of the web and its movement in one lateral direction or another is controlled by the lateral movement of the paper web in such manner that the respective movements of the web and the seam adhesive device are substantially simultaneous and in the same direction so that they move together step-by-step.

The accompanying drawings illustrate various forms of the invention, and therein:

Fig. 1 is a front elevation of one form of the invention, and

Fig. 2 is a corresponding end elevation.

Figs. 3 and 4 are, respectively, a front elevation and an end elevation of a modified form of the invention.

Figs. 5 and 6 are, respectively, a front elevation, and a diagrammatic view of associated mechanism, of another modified form of the invention.

Fig. 7 is an elevation of a further modified form of the invention, part of the mechanism being shown diagrammatically.

Fig. 8 shows, diagrammatically, the mechanism associated with the device shown in Fig. 7.

Figs. 9 and 10 are, respectively, a front elevation and an end elevation of a still further modified form of the invention.

fied form of the invention, part of the mechanism being shown diagrammatically.

Fig. 11 represents a wiring diagram suitable for use with the form of the invention shown in Figs.

5 1 and 2.

In the form of apparatus illustrated in Figs. 1 and 2 the seam adhesive device 10, hereinafter referred to as the paste box, comprises a box or dish 11 provided with bearings 12 on each end in which a spindle 13 is journaled. A pasting wheel 14 is mounted on the spindle 13 and its rim is adapted to depend into paste or other adhesive contained in the box 11 and on rotation apply said adhesive to paper with which it is adapted to make contact. The paste box 11 is provided at one end with a fork 15 adapted to rest on a sleeve 16, and at the other end with two forks 29 also adapted to rest on the sleeve 16 between which and secured thereto is a collar 17 mounted on the sleeve 16 and adapted to be moved along said sleeve 16 and be secured thereto in any desired position by a screw stud 18; thereby the paste box 10 is rigidly mounted on the sleeve 16; the position of the paste box 10 on the sleeve 16 may be adjusted as desired by sliding the collar 17 along the sleeve 16. The sleeve 16 is internally screw-threaded and is disposed on and adapted to engage an externally screw-threaded horizontal shaft 19 whereby the sleeve 16 will move along the shaft 19 when the said shaft is rotated. The shaft 19 is journaled in a frame 20 and is provided on one end with a worm wheel 21 which is engaged by a worm 22 on the shaft 27 of a motor 28; the motor 28 is adapted to rotate in either direction, controlled as hereinafter described, whereby the shaft 19 may be rotated in either direction.

A bracket 30 is also mounted on the sleeve 16 by means of a collar 31 thereon which is adapted to slide on a key 32 along the sleeve 16 so that it may be disposed in any desired position along the sleeve 16 relative to the paste box 10; the collar 31 is secured to the sleeve 16 by stud 33. The bracket 30 comprises a pillar 34 and a guide arm 35 provided with a bearing 36 adapted to engage and slide along a guide rod 37 which is parallel to the shaft 19. The engagement of the bracket 30 with the guide rod 37, through the guide arm 35, and with the sleeve 16 prevents the sleeve 16 rotating. Two arms 38, 39 are pivotally mounted on the upper end of the pillar 34, the outer ends of each of said arms being provided with rotatable electric contact members 40, 41. The arms 38, 39 are adapted to be drawn towards each other by a spring 42. The contact members 40,

41 are metallic and are in the form of wheels having a comparatively thin tread, for example, a knife-edge; they may be metallic brushes. Each of the contact members 40, 41 is connected by separate electric leads to the starting device of the electric motor 28, and they are preferably insulated from the arms 38, 39 on which they are mounted. The two contact members 40, 41 are adapted to make contact with a metallic roller 43, around which the paper web 44 is passed, in adjacent planes laterally of the said roller as shown in Fig. 2, one contact member 41 making contact with the roller 43 at a position slightly nearer to one end of the roller 43 than the position at which the other contact member 40 makes contact with the roller; the axis of the roller 43 is also disposed at right angles to the direction of travel of the paper web 44 and parallel to the axis of the shaft 19. The roller 43 is journaled in the frame 20. The contact members 40, 41 are pressed into contact with the roller 43 by the spring 42.

When the paper web 44 has been passed around the roller 43 the positions of the paste box 10 and of the bracket 30 are adjusted on the sleeve 16 so that the pasting wheel 14 makes contact with the web at the desired position, the contact member 40 makes contact with the paper web 44 close to the edge 45 thereof, and the contact member 41 makes contact with the roller 43 just outside the said edge 45 of the paper web. The paper web 44 will provide electric insulation between the contact members 40, 41 and the metallic roller 43. The electrical connections to the starting mechanism of the motor 28 are such that when both contact members 40, 41 are out of electric contact with the metallic roller 43, the motor 28 will rotate in one direction, when the contact member 41 alone is in contact with the roller 43 the motor will not rotate, and when both contact members are in contact with the roller the motor will rotate in the opposite direction; there will not be any position when the contact member 40 alone is in contact with the roller. Such electrical connections are arranged in any known manner and are not illustrated. It will be seen therefore that a slight lateral movement of the paper web 44 on the roller 43 will cause contact member 41 alone, or both contact members, or neither of the contact members, to be in electric contact with the roller 43.

The initial position is that shown in Fig. 1 where contact member 41 alone is in electrical contact with the roller 43, the motor 28 therefore being stationary. If, as the web 44 is travelling around the roller 43, it wanders laterally to the right (Fig. 1) so that it moves from under the contact member 40 whereby said contact member makes contact with the roller 43, the motor 28 is started up so as to rotate the shaft 19 and so move the sleeve 16 in the same direction as that in which the web 44 has wandered; the pasting wheel 14 is thereby moved with the web and the paste line is retained in its correct position on the web; simultaneously the bracket 30 carrying the contact members is also moved in the same direction until the position whereby only contact member 40 makes contact with the web 44 is restored, and the motor 28 will be stopped. If the web moves laterally in the other direction, that is, to the left (Fig. 1), so that it moves under the contact member 41 to remove the latter from contact with the roller 43, both contact members 40 and 41 will thereby be in contact with the web and the motor 28 will be

started up to rotate the shaft 19 and so move the sleeve 16 in the same direction, that is, to the left; thereby, the pasting wheel 14 will travel with the web and the bracket 30 will also move until the contact member 41 is moved from contact with the web 44 so that the initial position of the contact members is restored and the motor 28 is stopped.

A wiring diagram, suitable for use with the form of the invention illustrated in Figs. 1 and 2, is illustrated in Fig. 11. Two indirectly heated triode valves 101 and 102 are provided and are fed from rectifier 105; 103 and 104 are grid leaks for valves 101 and 102 respectively. The grid of the valve 101 is directly connected to the contact member 40, while the grid of valve 102 is directly connected to contact member 41. The earth connection 106 is on the roller 43.

20 Loading resistances 111, 112 and solenoids 107, 108 are inserted in the circuits of valves 101 and 102, respectively, the solenoids 107, 108 being energised when current is flowing through the respective valves. The solenoid 107 is adapted to actuate a switch 109, the said switch normally being closed when the solenoid 107 is not energised. The solenoid 108 is adapted to actuate a switch 110, the said switch normally being open when the solenoid 108 is not energised. Two three-way solenoid operated switching devices are 25 provided in the circuit of the motor 28. One of said switching devices comprises a solenoid 113 which is adapted to simultaneously actuate three switches 114, 115 and 116, the switch 114 normally being closed and the switches 115 and 116 30 normally being open when the solenoid 113 is not energised; the other switching device comprises a solenoid 117 which is adapted to actuate three switches 118, 119 and 120, the switch 118 normally being closed and the switches 119 and 120 35 normally being open when the solenoid 117 is not energised. The switches 109 and 114 are in the circuit of the solenoid 113 so that said solenoid is energised when said switches are closed; similarly the switches 110 and 118 are in the circuit 40 of the solenoid 117 so that said solenoid is energised when the said switches are closed. The three phase wires 121, 122 and 123 and the three terminals 124, 125 and 126 of the motor are connected to the two switching devices in the manner shown.

50 When the paper web is running correctly it insulates the contact member 40 from the roller 43 but allows the contact member 41 to make contact with the said roller. In these conditions the grid of valve 102 is at the same potential as the roller 43 and this prevents current flowing through valve 102. Sufficient current will flow in the valve 101 to energise the solenoid 107, the switch 109 thereby being opened. Neither of the solenoids 113 and 117 will be energised and the switches 114 and 118 will remain closed and the switches 115, 116, 119 and 120 will remain open, and no current will flow to the motor, which will remain stationary.

55 When the paper web wanders to the left, Fig. 1, so that it insulates both contact members 40 and 41 from the roller 43 both valves 101 and 102 allow sufficient current to flow to energise both solenoids 107 and 108, the switch 109 thereby being opened and the switch 110 closed. The circuit to solenoid 113 is thereby completed, through closed switches 110 and 118, whereupon the switch 114 is opened and the switches 115 and 116 closed. The phase wires 121, 122 and 123 are thereby 60 connected to terminals 124, 125 and 126, respec-

tively, of the motor, and the motor is caused to rotate in a direction to return the paper web to the right and restore its normal correct running position.

When the paper web wanders to the right, Fig. 1, so that both contact members 40 and 41 are in contact with the roller 43, neither of the valves 101 and 102 passes current, and neither of the solenoids 107 and 108 are energised; the switches 109 and 110 remain in their normal closed and open positions, respectively. The circuit to solenoid 117 will be completed, through closed switches 109 and 114, and switch 118 will be opened while switches 119 and 120 will be closed. Thereupon the phase wires 121, 122 and 123 will be connected to motor terminals 124, 126 and 125, respectively, and the motor will be caused to rotate in the opposite direction to return the paper web to the left and restore its normal correct running position.

In a modified form of the apparatus shown in Figs. 1 and 2, the sleeve 16 may carry only one contact making device which is normally adapted to make contact with the roller 43, the electric connections to the starting device of the motor 28 being such that the motor normally rotates so as to move the sleeve 16 continuously in one lateral direction, for example, to the right, Fig. 1; the transverse movement of the sleeve and the contact making device will move the contact making device towards one edge of the paper web; when the contact making device moves on to the web the contact between the said member and the roller 43 will be broken and the motor will be operated to reverse the direction of movement of the sleeve 16 and so restore the normal position with contact-making member in contact with the roller 43. If the web wanders to the right the contact making device will follow it up until the web ceases to wander and the device moves on to the web; if the web wanders to the left it will at once move under the contact making device; in both cases the direction of travel of the contact making device and of the paste box will be reversed until the contact making device again makes contact with the roller 43. Alternatively, the contact making roller may normally be in contact with the web, the reverse movement of the sleeve being affected when the said member moves off the web on to the roller.

It will be obvious that instead of the paste-box 10 being moved with the sleeve 16 the apparatus may be modified so that only the pasting wheel 14 in the box may be moved with the sleeve. It is also obvious that the paste-box may be connected to the sleeve in any suitable manner so as to travel therewith; for example, the paste-box may be mounted on a rod or shaft parallel to the shaft 19 and be connected to the sleeve 16 by suitable link or other devices.

It will also be obvious that the invention may be applied to seam adhesive devices other than paste-boxes, for example, devices applying a paste line by means of a gravity feed or pump; the said devices may be moved laterally of the web in manners similar to those described with reference to a paste-box.

The electric contact making device may be associated with a roller other than that directly associated with the seam adhesive device.

In the modified form shown in Figs. 3 and 4 two photoelectric cells 46, 47 are mounted on and fixed to a rod 48 disposed parallel to the shaft 19. The positions of the cells 46, 47 on the rod

may be adjusted by any suitable means so that the light beam to the scanning head of the cell 46 is normally interrupted by one edge of the paper web 44, and the light beam to the scanning head of the cell 47 is normally interrupted by the other edge of the web 44. The rod 48 is supported in bearings in the frame 20 and is adapted to slide axially in said bearings. A link 51 is rigidly secured at one end to the rod 48 and at the other end to the sleeve 16 so that the rod 48 and sleeve 16 will move simultaneously transversely of the frame 20. When the light beams to both photoelectric cells 46, 47 are interrupted the motor is stationary. When the light beam of the cell 46 is allowed to pass to its scanning head an electric circuit is completed to cause the motor 28 to rotate in such a direction that the sleeve 16 together with the paste-box 10 and the rod 48 are moved to the right, Fig. 3, and when the beam of cell 47 passes to its scanning head the motor is rotated to cause the sleeve 16, paste-box 10 and rod 48 to move to the left, Fig. 3. It will therefore be seen that when the paper web 44 wanders to the right, Fig. 3, it will move out of the path of the light beam to the scanning head of photo-electric cell 46 and the motor will operate to move the paste-box to the right with the web 44, and the rod 48 will also be moved to the right until the position is restored with both light beams interrupted. Similarly, if the web wanders to the left, the cell 47 will operate the motor to move the paste-box 10 and the rod 48 to the left.

In the form of apparatus shown in Figs. 5 and 6 the sleeve 16 is adapted to be moved intermittently laterally of the machine by a ratchet device, the coacting pawl being continuously operated by a motor. As will be seen in Fig. 6, 40 a motor 71 drives a vacuum pump 52 through gearing 53, the said drive being continuous. The pump 52 is connected by a pipe 54 to a nozzle 55, Fig. 5, and to a cylinder 56. The nozzle 55 is supported by a bracket 57 rigidly mounted on the sleeve 16 so as to move therewith, and the nozzle is so disposed that the paper web 44 is in contact with the outer surface thereof and so that a hole 58 in the nozzle is normally just uncovered by the edge of the web 44. When the hole 58 is uncovered, air is drawn therethrough and through the pipe 54 by the pump 52. Two ratchet wheels 59, 60 are rigidly mounted on the spindle 19, or on another spindle coupled thereto by coupling 41, the teeth of the wheel 59 being directed in the opposite direction to the teeth on wheel 60. A lever 62 is rotatably mounted on the spindle 19, between the ratchet wheels 59 and 60, and carries at its upper end two pawls 63 and 64 directed in opposite directions, the pawl 63 being adapted to coact with ratchet wheel 59, and the pawl 64 being adapted to coact with ratchet wheel 60. The lower end of the lever 62 is connected by a connecting rod 65 to a crank pin 66 eccentrically disposed on a toothed gear wheel 67 which is in mesh with one of the wheels of gearing 53. The two pawls 63, 64 are rigidly mounted on a short spindle 68 rotatably mounted in the upper end of the lever 62, the pawls 64 being connected by rod 69 to a plunger 70 in the cylinder 56. It will be seen that the motor 71 in addition to driving the pump 52, causes the lever 62 to oscillate and, according to which pawl 63, 64 is in engagement with its ratchet wheel 59, 60, to rotate the spindle 19 in one direction or the other. When the

hole 58 in the nozzle 55 is uncovered by the web 44 air will be drawn therethrough by pump 52, and the plunger 70 will descend gravitationally in the cylinder 56 and allow the pawl 64 to engage the teeth of the ratchet wheel 60; thereby the spindle 19 is rotated intermittently so as to move the sleeve 16, paste-box 10, and nozzle 55 to the left, Fig. 5. As soon as the hole 58 moves under the web 44, and is covered thereby, air will cease to be drawn through said hole, and the pump 52 will draw the plunger 70 up in the cylinder 56. The pawl 64 will be drawn out of engagement with the ratchet wheel 60, and the pawl 63 will be moved into engagement with the ratchet wheel 59 whereby the spindle 19 is rotated in the opposite direction and the paste box 10 and nozzle 55 are moved to the right, Fig. 5. The hole 58 will be again uncovered by the web 44 and the cycle of operations will be repeated. If the web 44 should wander to the right the hole 58 will be covered, the rotation of the spindle 19 reversed and the paste-box 10 will also move to the right. If the web 44 should wander to the left the paste box 10 and nozzle 55 will follow it until the hole 58 is covered again by the web. It will be seen that the paste box is continuously moving, its direction of movement being determined by whether the hole 58 in the nozzle is covered or not. Part of the pipe line 54 may be flexible to allow of movement of the nozzle 55.

In the form shown in Figs. 7 and 8 the vacuum pump 52 is connected as before by pipe 54 to nozzle 55 which is provided with a hole 58 adapted to be covered or uncovered by the web 44. The nozzle is secured by bracket 57 to the sleeve 16. When the hole 58 is covered, the pump 52 will draw the plunger 70 down in the cylinder 56 against the action of a spring 72. Two electric switches 73 and 74 are mounted on a base 75 and are so connected in the circuit of the motor 28 that when the switch 73 is closed the motor 28 is rotated so as to move the sleeve 16 to the right, and when the switch 74 is closed the sleeve 16 is moved to the left. A lever 76 is pivotally mounted on the base 75, and one end thereof is connected by the tension spring 72 to the base 75; the lever 76 is also connected by rod 65 to the plunger 70. When the lever 76 is drawn down by the plunger 70 against the action of spring 72 it makes contact with the switch 74 and closes said switch; when it is raised by the spring it engages and closes the switch 73. It will be seen that if the nozzle 55, when the hole 58 is uncovered, moves to the right, or the web 44 moves to the left, so that the hole 58 becomes covered by the web, the plunger 70 will be drawn down by the pump 52, the lever 76 will be drawn down to break the switch 73 and close the switch 74, and the motor 28 will operate to move the sleeve 16 and nozzle 55 to the left. Similarly, when the nozzle moves to the left, or the web to the right, to uncover the hole 58, air will be drawn through the said hole, the plunger 70 will be released and the spring 72 will draw the lever 76 to break the switch 74 and close the switch 73, the motor 28 thereby operating to move the nozzle to the right.

In the form shown in Figs. 9 and 10, a light roller 77 is freely mounted on a spindle 78 so that it may rotate and slide axially thereon. Two flanged bushes 79, 80 are rigidly secured to the roller 77 by screw studs or other suitable means so that they may be adjustably positioned on the said roller for the end face of one bush

19 to engage one edge of the paper web 44, and the end face of the other bush 80 to engage the other edge of the web. Two electric switches 73 and 74 are mounted on brackets 83, 84, adjustably mounted on a carrier 81 which is rigidly mounted on an arm 82 in turn rigidly mounted on the sleeve 16 so that the two switches may move to left or right simultaneously with the sleeve. The switches 73, 74 are spaced slightly further apart than the bushes 79, 80, and so positioned that the bushes may move into contact with and close said switches. When bush 80 is in contact with and closes switch 74 the bush 79 is out of contact with switch 73 and said switch 73 is open, and vice-versa. Normally, when the web 44 is running true, both bushes 79, 80 are out of contact with the switches 73, 74 and both of said switches are open. If the web 44 wanders to the left it will push the bush 79 to the left, together with the roller 77 and bush 80, and the bush 79 will engage the switch 73, closing said switch. When switch 73 is closed a circuit of the motor 28 is closed whereby said motor rotates in such a direction as to cause the sleeve 16 together with paste box 10, arm 82, carrier 81, and switches 73, 74, to move to the left substantially synchronously with the web 44. When the web ceases to wander, the carrier 81 will continue to move to the left until the switch 73 is out of contact with bush 79 whereupon the said switch will open and the motor will stop. Similarly, the switch 74 will be closed when the web wanders to the right, and the motor 28 will rotate to cause the sleeve 16 to move to the right.

By the use of the invention a marked reduction in production costs is obtained, it being unnecessary to provide a large overlap on the paper forming the tube to allow for wandering of the paste line.

The device may be used in conjunction with an automatic reel control as used on slitting machines.

The invention may be applied to machines 45 wherein waxed or other papers are caused to adhere to each other by the application of heat, where Cellophane or other papers or papers provided with a dry adhesive are caused to adhere to each other by the application of pressure. In 50 such cases the heat or pressure sealing device is caused to follow the wandering paper in the manner hereinbefore described with reference to the paste box.

What I claim and desire to secure by Letters 55 Patent is:

1. In a paper bag making machine, a rotatable roller supporting a paper web for traveling movement, an externally threaded shaft mounted for rotation in parallel relation to said roller and disposed laterally of the direction of travel of the paper web, an internally threaded sleeve in threaded engagement with said shaft whereby rotation of said shaft will cause said sleeve to move laterally of the direction of travel of the paper web, a seam adhesive device supported on said sleeve and movable therewith laterally of the paper web; said seam adhesive device having an adhesive-applying rotary disc member normally in contact with said paper web adjacent one edge thereof for applying a narrow layer of adhesive to the paper web, a bi-directional rotary device connected to said shaft for rotating it in either direction, and means responsive to lateral movement of the paper web on said roller for determining the direction of rotation of said rotary

device, whereby the seam adhesive device is moved in the same direction as and substantially simultaneously with the paper web.

2. In a paper bag making machine a rotatable roller supporting a paper web for traveling movement, said roller being of electrical conducting material, an externally threaded shaft mounted for rotation in parallel relation to said roller and disposed laterally of the direction of travel of the paper web, an internally threaded sleeve in threaded engagement with said shaft whereby rotation of said shaft will cause said sleeve to move laterally of the direction of travel of the paper web, a seam adhesive device supported on said sleeve and movable therewith laterally of the paper web; said seam adhesive device having an adhesive-applying member normally in contact with said paper web adjacent one edge thereof, a bi-directional electric motor geared to said shaft for rotating it in either direction, and switching means in the circuit of said motor and having a pair of contacts one normally in contact with said roller and the other resting on said paper web and thereby insulated from said roller, the organization being such that lateral movement of the paper web on its roller in one direction will permit both contacts to contact with the roller thereby closing the circuit and causing the motor to rotate in one direction and lateral movement of the paper web in the opposite direction will insulate both contacts from said roller and cause the motor to rotate in the opposite direction.

3. In a paper bag making machine as set forth in claim 2, said contacts being mounted on a bracket secured to said sleeve and disposed at diametrically opposite sides of the roller.

4. Paper bag making machinery according to claim 1, wherein an air suction pump is provided and is adapted to be continuously operated, the said pump is connected by a pipe line to a nozzle mounted on the said sleeve so as to travel therewith, an air inlet orifice in said nozzle is adapted

to be disposed adjacent to one edge of the paper web so as to be covered or uncovered by said web when the web wanders laterally, a cylinder is also connected by a pipe line to said air pump, a plunger in said cylinder is connected to a lever adapted to operate either of two electric switches according to the position of the plunger in the cylinder, the said switches are disposed in circuits of a bi-directional electric motor in such manner that the motor is caused to rotate in either direction according to which switch is closed, the plunger is adapted to be moved in one direction in the cylinder by the air pump when the air inlet orifice in the nozzle is covered, and a spring is provided to move the plunger in the opposite direction in the cylinder when the said nozzle is uncovered.

5. Paper bag making machinery according to claim 1, wherein a freely rotatable and axially movable roller is disposed on an axis laterally of the direction of travel of the paper web, two bushes are mounted on said roller and positioned so that they engage the edges of said web and are caused to move laterally by the web when the web wanders, two electric switches are mounted on the said sleeve so as to move therewith and are positioned in relation to said bushes whereby either of said switches is operated by said bushes when the said roller moves axially, the said electric switches being disposed in circuits of a bi-directional electric motor in such manner that the motor is caused to rotate in either direction according to which of the said switches is closed.

JOHN NICHOLAS.
